(57) **CLAIM**

The ornamental design for a vehicle fairing, as shown and described.

DESCRIPTION

FIG. 1 depicts a front, top, left perspective view of a vehicle fairing showing my new design.

FIG. 2 depicts a front, right, bottom view thereof;

FIG. 3 depicts a front view thereof;

FIG. 4 depicts a back view thereof;

FIG. 5 depicts a left side view thereof;

FIG. 6 depicts a right side view thereof;

FIG. 7 depicts a top view thereof; and,

FIG. 8 depicts a bottom view thereof.

The ghosted or low contrasted portions of the vehicle fairing illustrate portions that form no part of the claimed design. The dash lines depict boundaries of the claimed design.

1 Claim, 8 Drawing Sheets
